UNITED STATES PATENT OFFICE.

MARTIN BOYER, OF ELBOW LAKE, MINNESOTA, ASSIGNOR OF TWO-THIRDS TO EDWARD J. SCOFIELD AND TOSTEN E. DYBDAL, OF ELBOW LAKE, MINNESOTA.

STIRRUP.

No. 859,480.

Specification of Letters Patent.

Patented July 9, 1907.

Application filed March 4, 1907. Serial No. 360,432.

To all whom it may concern:

Be it known that I, MARTIN BOYER, a citizen of the United States, residing at Elbow Lake, in the county of Grant and State of Minnesota, have invented a new and useful Stirrup, of which the following is a specification.

This invention relates to a safety stirrup of that type in which the foot plate, hinged to the inner leg of the stirrup is detachably secured at its opposite end to the other leg of the stirrup; and the object of the invention is to provide a simple and safe locking device for fastening the free ends of the foot plate in operative position, whereby it is secured from disengagement by any amount of pressure the rider may place on the foot plate, or any rocking motion of the foot while the rider is in the saddle. In connection with the locking device is a pivoted bow standing normally in a forwardly inclined position with the crown of the bow arch above the rider's instep and so placed that if the rider is thrown or unseated, the toes of his boots will act on the bow of each stirrup and cause them to unlock the foot plates and release the feet of the rider.

With this object in view the invention consists in the peculiar combination and arrangement of parts hereinafter described and definitely claimed.

In the accompanying drawings: Figure 1 is a perspective view of the left stirrup as seen from the front, the foot plate being disengaged and partly swung downward. Fig. 2 is a view of the outer side of the stirrup with the foot plate in position and locked. Fig. 3 is a detail perspective view of a portion of the stirrup showing the foot plate forked for engagement with a projection on one of the side legs.

Similar numerals of reference indicate the same parts in the figures.

The stirrup which has the general form of those now in use, comprises a bow 1, an outer leg 2 and an inner leg 3. A loop 4 is connected to the bow 1 for attachment to the usual stirrup strap. The lower end of the outer leg 2 is forked as shown at 5 above which fork is hinged a hook 6 on a pivot 7. The lower end of the inner leg is formed into a boss which serves as one part 8 of a hinged joint for the inner end 9 of the foot plate 10. A pin 11 passes horizontally through the boss 8 and the inner end of the foot plate 9 to serve as the pintle for the hinge joint. Springing from the hook 6 above its pivotal connection to the outer leg 2 is an inner bow 12 the other end 13 of which is pivotally connected to the inner leg 3 by a pin 14 in line with the pivot 7 on the opposite leg. The height of the bow is such that when the rider's foot is resting on the foot plate the usual motions of the foot may be made without touching or dangerously moving the bow, but if an accident should occur and the rider be dismounted or thrown the toe of his boot would catch the bow and swing it on its pivots.

The foot plate 10, as before stated is pivoted to the inner bow 3. The outer end of the foot plate terminates in a T-shaped projection 15, the stem 16 of which passes, when the foot plate is in operative position, between the prongs of the fork 5 on the lower end of the outer leg 2. The lugs 17 on the cross piece 18 of the T head projection 15 pass around and brace the front and rear sides of the prongs of the fork 5, respectively, thereby holding the foot plate rigidly in position and preventing it from rocking. The bow 12 is now swung forward until the hook 6 passes beneath the projection 15, as clearly illustrated in Fig. 2, the bow assuming the forwardly inclined position there shown. In this position the weight of the bow being thrown forward of the vertical plane of the pivot 7 serves to maintain the hook 6 in locked position, and thus prevent accidental unlocking and release of the foot plate when mounting or dismounting.

It will be understood that instead of a fork 5 on the end of the leg 2 straddling the projection of the foot plate, a pin 19 may be substituted for the fork and the projection on the foot plate provided with a perforation for said pin, or itself be forked as shown in Fig. 3.

When riding, the stirrup is in the position represented in Fig. 2, the foot plate is in engagement with the outer leg of the stirrup, the hook 6 extending under the projection 15 of the foot plate and the inner bow inclined forwardly. Should the rider be thrown or dismounted his foot, rocking on the foot plate as a fulcrum would cause the toe of his boot to be raised to such a height as to strike the inner bow 12 and raise it to the substantially vertical position, shown in Fig. 1. This would cause the hook 6 to swing forwardly on its pivot and pass from beneath the projection 15 of the foot plate, which latter being relieved of any outside support would swing downwardly and release the rider's foot from the stirrup.

Having thus described the invention, what is claimed is:—

The combination in a stirrup having inner and outer legs, of a foot plate pivoted to the inner leg and adapted to swing downward by gravity, the opposite end of the foot plate and the lower portion of the outer leg having interengaging members to prevent independent lateral play, a pivoted bow arranged within the legs, said bow having at one end a curved hook adapted to engage under the free end of the foot plate and hold the same locked to the outer leg, the bow when in locking position being inclined forward, so that its weight tends to maintain the hook in locked position.

In testimony that I claim the foregoing as my own, I have hereto affixed my signature in the presence of two witnesses.

MARTIN BOYER.
